UNITED STATES PATENT OFFICE.

JOHN EDWARD NACE, OF HANOVER, PENNSYLVANIA.

WINDING DEVICE FOR LACES.

965,648.

Specification of Letters Patent. Patented July 26, 1910.

Application filed January 21, 1910. Serial No. 539,296.

To all whom it may concern:

Be it known that I, JOHN E. NACE, a citizen of the United States, and a resident of Hanover, in the county of York and State 5 of Pennsylvania, have invented a new and Improved Winding Device for Laces, of which the following is a full, clear, and exact description.

My invention relates to winding devices, 10 my more particular purpose being to provide an improved type of hand-operated winder for use in connection with laces.

More specifically stated, my invention comprehends a hand winder adapted for 15 winding lace upon a spool, and further comprehends means for readily exchanging one spool for another.

Reference is to be had to the accompanying drawings forming a part of this specification, in which similar characters of reference indicate corresponding parts in all the figures.

Figure 1 is a view partly in front elevation and partly broken away, showing my 20 improved winding device ready for use; Fig. 2 is a side elevation showing the mechanism appearing in Fig. 1, but viewed as from a point at the left of Fig. 1; Fig. 3 is a detail showing in horizontal section the 25 means for locking the handle relatively to the spool; and Fig. 4 is a section on the line 4—4 of Fig. 2, looking in the direction of the arrow.

Mounted upon a wall 5 is a socket 6. A 30 bracket 7 is provided with a vertical portion 8 adapted to fit into the socket 6. This socket is secured against the wall by aid of screws 9. The bracket 7 is provided with arms 10, 11 integral with it and extending 35 in opposite directions, these arms being bent upward. The arm 10 is provided with a fork one prong 10^a of which extends higher than the other prong 10^b.

At 12 is a latch made preferably of thick 40 sheet metal and provided with a foot 13. A pin 14 extends through the latch and into the arm 10. The latch swings upon the pin 14, so that the foot 13 may be brought up over the center of the fork, as will be understood from Fig. 2. A spool 14^a is provided 45 with conical ends 15, and extending through this spool is a shaft 16, one end of this shaft being provided with a spiral groove 17. A sleeve 18 is mounted upon a threaded shaft 50 19, this shaft being integral with a handle 20. The shaft 19 is provided with an en-

larged portion 21 and extends through a bearing in the upper end of the arm 11. The enlarged portion 21 serves as a limiting stop for preventing the shaft 19 from having too great play relatively to the arm 11. A handle 22 is mounted upon the crank 20 for the purpose of turning the same. At 19^a is a pin carried by the sleeve 18 and extending radially into the spiral groove 17 of the 55 shaft 16.

The operation of my device is as follows: To remove the spool 14^a the latch 12 is swung sidewise upon the pin 14 as a center. The foot 13 of the latch thus clears the adjacent end of the spool. The spool carrying with it the shaft 16 is now raised upwardly at the left according to Fig. 1. The handle 22 meanwhile being turned slightly, the pin 19^a follows the spiral groove 17 and the 70 shaft 16 is thus taken bodily out. The sleeve 18 remains tightly fitted upon the threaded shaft 19. To insert another spool, the shaft 16 is first threaded through the spool and the end of the shaft is brought into such position that the pin 19^a follows the groove 17. To facilitate the entrance of the shaft into the sleeve 18 the handle 22 is slightly turned. Meanwhile the opposite end of the 75 shaft 16 is forced down into the fork 11. The latch 12 is next swung up into position, so that the foot 13 rests against the adjacent end of the spool.

In order to wind tape upon the spool, the 80 end of the tape is brought into contact with the body portion of the spool and the handle 22 is rotated. The tape is thus wound around the spool and as the rotation continues, the spool is gradually filled. The bracket 7 is 85 detachable from the socket 6—that is to say, by grasping the bracket 7 and raising it bodily upward the downturned portion of this bracket is readily withdrawn from the socket 6.

My invention is of peculiar value in relation to cabinets used for holding spools of laces, as it is desirable to wind the laces upon the spools before they are inserted in the cabinet.

Having thus described my invention, I 100 claim as new and desire to secure by Letters Patent:

1. A winding device for laces, comprising a socket, a bracket provided with a portion for extending into said socket, and further 105 provided with a horizontal portion and with arms extending parallel with each other

from said horizontal portion, a latch mounted upon one of said arms and provided with a foot for engaging a spool, a shaft journaled upon the other of said arms and adapted to be turned, a crank for rotating said last-mentioned shaft, a sleeve mounted upon said last-mentioned shaft, a pin carried by said sleeve and extending internally thereof, and a shaft provided with a groove 10 for receiving said pin, said shaft being of proper form to extend through a spool.

2. In a winding device for laces, the combination of an arm, a shaft journaled relative to the arm, a sleeve mounted upon the shaft, a pin carried by the sleeve and extending internally thereof, and a shaft provided with a groove 15 for receiving said pin, a crank for turning said shaft, a sleeve mounted upon said shaft, a pin carried by said sleeve and extending internally thereof, and another shaft provided with a spirally disposed groove for receiving said pin.

In testimony whereof I have signed my name to this specification in the presence of two subscribing witnesses.

JOHN EDWARD NACE.

Witnesses:

EDWARD A. MICHAEL,
C. M. WINEKENNER.
